UNITED STATES PATENT OFFICE.

DANIEL APPLEGATE, OF NOBLESVILLE, INDIANA.

IMPROVEMENT IN CLOD-FENDERS.

Specification forming part of Letters Patent No. 94,268, dated August 31, 1869.

To all whom it may concern:

Be it known that I, D. APPLEGATE, of Noblesville, in the county of Hamilton, and in the State of Indiana, have invented certain new and useful Improvements in Clod-Fenders; and I do hereby declare that the following is a full, clear, and exact description thereof, reference being had to the accompanying drawing, and to the letters of reference marked thereon, making a part of this specification.

The nature of my invention consists in the construction of an adjustable clod-fender, which can be raised and lowered so as to suit the depth of plowing, as will hereinafter be more fully set forth.

The accompanying drawing represents a perspective view of my invention.

Letter A represents an ordinary plow or cultivator, to which the fender is attached. To the side of the beam there is secured a metal plate, B, which has a vertical elongated slot cut in each end, so that it can be lowered and raised at pleasure, and is held at any desired point by means of bolts or screws. If desired, only one of these ends need be slotted, while

the other merely turns upon a pivot. Extending out and backward from this plate there are a number of curved metal rods, C, which form the fender. These rods have their rear ends turned slightly upward, and, being elastic, they slip easily and readily over stones or any obstructions which they may strike, and, having their ends open, the rubbish and dirt can pass freely out. By raising and lowering the plate B these rods can be adjusted to any desired depth of plowing.

Having thus described my invention, what I claim, and desire to secure by Letters Patent, is—

The arrangement upon the side of a plow or cultivator beam, A, of the slotted plate B and curved rods C C, all constructed substantially as specified.

In testimony that I claim the foregoing I have hereunto set my hand this 29th day of June, 1869.

DANIEL APPLEGATE.
